UNITED STATES PATENT OFFICE

117,586

DESIGN FOR A NEWSSTAND

Sebastian J. Tauriello, Buffalo, N. Y.

Application July 21, 1939, Serial No. 86,171

Term of patent 14 years

To all whom it may concern:

Be it known that I, Sebastian J. Tauriello, a citizen of the United States, residing at Buffalo, in the county of Erie and State of New York, have invented a new, original, and ornamental Design for a Newsstand, of which the following is a specification, reference being had to the accompanying drawings, forming part thereof.

In these drawings:

Fig. 1 is a perspective view of the newsstand, viewed from the front and showing the stand closed with one window open.

Fig. 2 is a view similar to Fig. 1 viewed from the rear.

Fig. 3 is a view similar to Fig. 1 showing the newsstand opened.

Fig. 4 is a view similar to Fig. 2 showing the newsstand opened and the display panels in a somewhat different position from that shown in Fig. 3.

I claim:

The ornamental design for a newsstand, as shown.

SEBASTIAN J. TAURIELLO.
